WEATHER INSTRUMENT

Moto Shimano, Los Angeles, Calif., assignor to General Controls Co., Glendale, Calif., a corporation of California

Filed June 22, 1961, Ser. No. 65,689

Term of patent 14 years

(Cl. D52—7)

FIG. 1.

FIG. 2.

FIG. 3.

FIG. 4.

FIGURE 1 is a front elevation of a weather instrument showing my new design.

FIGURE 2 is a top plan view of the same.

FIGURE 3 is an end elevation.

FIGURE 4 is a section taken along line 4—4 of FIGURE 1.

The undisclosed end and rear of the weather instrument are substantially plain in appearance.

I claim:

The ornamental design for a weather instrument, as shown and described.
